UNITED STATES PATENT OFFICE.

ALFRED A. GLIDDEN, OF WATERTOWN, MASSACHUSETTS, ASSIGNOR TO HOOD RUBBER COMPANY, OF WATERTOWN, MASSACHUSETTS, A CORPORATION OF MASSACHUSETTS.

DESIGN FOR A RUBBER BOOT.

Application filed January 12, 1923. Serial No. 4,866. Term of patent 14 years.

To all whom it may concern:

Be it known that I, ALFRED A. GLIDDEN, a citizen of the United States, residing at Watertown, in the county of Middlesex and Commonwealth of Massachusetts, have invented a new, original, and ornamental Design for a Rubber Boot, of which the following is a specification, reference being had to the accompanying drawing forming part thereof.

In this drawing, Figure 1 is a side elevation showing my new design; and Fig. 2 is a rear elevation on a slightly larger scale with the lower part broken away.

I claim:

The ornamental design for a rubber boot, as shown.

ALFRED A. GLIDDEN.
